(57) **CLAIM**

The ornamental design for a trailer hitch alignment device, as shown and described.

DESCRIPTION

FIG. 1 is a front perspective view of a trailer hitch alignment device, showing my new design;

FIG. 2 is a rear perspective view thereof;

FIG. 3 is a top plan view thereof;

FIG. 4 is a bottom plan view thereof;

FIG. 5 is a front plan view thereof;

FIG. 6 is a rear plan view thereof;

FIG. 7 is a left side plan view thereof;

FIG. 8 is a right side plan view thereof; and,

FIG. 9 is a top perspective view, illustrating a trailer hitch alignment device in an open configuration for receiving a trailer hitch.

The broken lines in FIGS. 1-9 are included for the purpose of illustrating environment and form no part of the claimed design.
